UNITED STATES PATENT OFFICE.

HEBER HOY, OF PARKERSBURG, WEST VIRGINIA.

CHAIN FASTENER.

Application filed August 2, 1922. Serial No. 579,214.

To all whom it may concern:

Be it known that I, HEBER HOY, citizen of the United States, residing at Parkersburg, in the county of Wood and State of 5 West Virginia, have invented certain new and useful Improvements in Chain Fasteners, of which the following is a specification.

This invention relates to an improved fastening for non-skid chains or other flexible elements and seeks, as one of its principal objects, to provide a device which may be effectually locked against accidental release while, when desired, the device may be easily and quickly disengaged. The invention has as a further object to provide a device wherein endwise pull or tension upon the device will serve to maintain the device locked.

And the invention has as a still further object to provide a device which will be characterized by structural simplicity, which will not be liable to break or get out of order, and which will be adapted for a wide range of use.

Other and incidental objects will appear hereinafter.

In the drawings:

Figure 1 is a side elevation of my improved fastening showing the device locked. 30 Figure 2 is a sectional view also showing the device locked.

Figure 3 is a view similar to Figure 2, showing the manner in which the device is released.

35 Figure 4 is a top plan view of the device, the cover employed being in section, and

Figure 5 is a detail perspective view showing the body member of the device.

In carrying the invention into effect, I 40 employ a flat body member 10 bent over at one end to provide a boss 11 preferably secured by a rivet 12 and formed in said boss at its forward end is a squared notch 13. In advance of said notch, the body member is provided with a longitudinally directed slot 14 while near its forward end said member is cut away from the upper edge thereof to define an upwardly presented hook 15 at the forward terminal of the member. In the 45 rear of said hook, the body member is provided with a vertically disposed shoulder 16 and sloping from the upper end of said shoulder rearwardly to the upper edge of the member is an inclined face 17.

In conjunction with the body member, I 50 employ a latch 18 cut away at its lower

edge to provide a downwardly presented hook 19. In the rear of said hook, the member is provided with an inclined face 20 sloping downwardly and rearwardly to the 60 lower edge of the member and formed on said member at its inner end is a lug 21 adapted to fit in the notch 13 of the boss 11 of the body member. Extending through the member 18 and freely through the slot 65 14 of the member 10 is a bolt or other suitable fastening device 22 slidably and pivotally connecting the latch member with the body member.

Pivoted upon the bolt 22 is a channel 70 shaped cover 23 adapted to snugly fit over the forward ends of the members 10 and 18, the sides of the cover being formed to receive the bolt therethrough. Near the forward end of the cover, the sides thereof are 75 provided with oppositely disposed notches 24 having rounded rear walls 25 curving downwardly and rearwardly to the lower edges of said sides, and looped at its ends about the end portions of the bolt to overlie 80 the sides of the cover is a link 26 of a chain, the link at the opposite end of the chain being indicated at 27.

In use, the link 26 is grasped and pressed 85 forwardly for riding the bolt 22 forwardly within the slot 14 of the body bar 10 and accordingly shifting the latch member 18 forwardly upon the body member when, as suggested in Figure 3, the latch member, with the cover 23, may be swung upwardly 90 95 to clear the hook 15. Accordingly, the link 27 may then be engaged with said hook when the latch member is then again closed downwardly to engage the hook 19 thereof through said link. The cover 23 is then closed downwardly over said hooks, the link 27 being received through the notches 24 in the sides of the cover. A slight pull in opposite directions is then exerted upon the links 26 and 27 for again shifting the latch 100 member 18 rearwardly upon the body member 10 to engage the lug 21 of the latch member in the notch 13 of the boss 11. Thus the fastening is engaged with the link 27, the link being confined between the latch 105 member and the body member 10 to engage the hooks 15 and 19 thereof, it being observed that when the latch member is closed, said hooks register at their inner edges. Pull in opposite directions upon the links 110 26 and 27 will, of course, serve to exert a rearward pull upon the latch member so

that the lug 21 of said member will be retained within the notch 13 of the boss 11 for locking the latch closed. Accidental release of the fastening will thus be prevented.

To detach the fastening from the link 27, the links 26 and 27 are grasped and shifted endwise toward each other. This movement of the links will serve to ride the link 27 beneath the inclined edges 25 of the cover 23, as shown in Figure 2, for shifting the cover upwardly, the link shifting into engagement with the stop shoulder 16 for limiting the body member 10 against forward movement. Accordingly, as the link 26 is advanced, the latch member 18 will, as shown in Figure 3, be shifted forwardly upon the body member 10 to disengage the lug 21 of the latch member from within the notch 13, while the inclined face 20 of the latch member will be coincidentally advanced over the link 27 for rocking the free end of the latch member upwardly. As the movement of the links 26 and 27 towards each other is then continued, the link 27 will be caused to ride out of engagement with the shoulder 16 up the inclined face 17 of the body member to complete the upward swinging movement of the latch member to open position, the cover 23, of course, being swung upwardly with the latch member. Thus, the fastening may be released with a minimum of difficulty.

Having thus described the invention, what is claimed as new is:

1. A device of the character described including a body member provided with a notch, a latch member having a lug, and means pivotally mounting the latch member

and slidable upon the body member for shifting the latch member to engage the lug thereof in said notch locking the latch against pivotal movement.

2. A device of the character described including a body member provided at one side thereof with a boss having a notch in its forward edge, the body member being formed with a longitudinally directed slot, a latch member provided at its rear end with a lug, and a bolt pivotally mounting the latch member extending freely through said slot slidably supporting the latch member for endwise movement to engage the lug thereof in said notch locking the latch against pivotal movement.

3. A device of the character described including a body member, a latch member, means pivotally mounting one of said members and slidable upon the other of said members for shifting the pivoted member into engagement with the other of said members locking the pivoted member against pivotal movement, and a cover pivoted upon said means normally fitting over the latch and body members.

4. A device of the character described including a body member provided with a notch, a latch member slidably and pivotally connected with the body member and provided with a lug projecting from the rear end of the latch, and means slidably and pivotally connecting the latch with the body member, the latch being shiftable to engage said lug in said notch locking the latch independent of said means against pivotal movement.

In testimony whereof I affix my signature.
HEBER HOY. [L.S.]
